UNITED STATES PATENT OFFICE.

FRANCIS E. BUXTON, OF INDIANAPOLIS, INDIANA.

JOURNAL-BEARING.

1,313,466.

Specification of Letters Patent. Patented Aug. 19, 1919.

Application filed June 22, 1918. Serial No. 241,328.

To all whom it may concern:

Be it known that I, FRANCIS E. BUXTON, a citizen of the United States, residing in the city of Indianapolis, in the county of Marion, State of Indiana, have invented certain new and useful Improvements in Journal-Bearings, of which the following is a full, clear, and comprehensive specification, the same being such as will enable others to make and use the same with precision.

My present invention has special reference to heavy duty bearings, wherein the exact alinement of a supported journal or shaft is maintained, the specific feature being the means provided to automatically and positively cause the bearings to continuously creep or roll under the revolving journal for the purpose of distributing the wear evenly within the sleeves and also to cause the lower section of the same to continuously pass through a head of oil.

Another object is to provide a justifying bearing having a plurality of inner duplicate tapered sleeves supported by a suitable outer sleeve in a manner that the reduced ends of the inner sleeves may be drawn together for the purpose of forming a complete wear compensating bearing, relating in particular to a universal type.

In the accompanying drawings, forming a part of this specification, the manner and the means provided to accomplish the desideratum is most clearly shown, in which: Figure 1 is an end elevation of the bearing, having certain parts broken away to show the reducing-drive worms which are mounted therein. Fig. 2 is a side view of the complete bearing, taken partly in section on the line A—B of Fig. 1. Fig. 3 is an inner end elevation of one of the bearing-cage members, the bearing sleeve having been removed and the cage shown at a one-eighth turn relative to Fig. 2. Fig. 4 is a side elevation of the cage member and also showing, in diametrical section, its oil retaining gland and the position of its fiber ring. Fig. 5 is a side elevation of one of the bearing sleeves, the lower portion being shown as broken away and shown in section. Fig. 6 is an end elevation of the container sleeve,

the lower half being broken away and shown in section, as on the line C—D of Fig. 7. Fig. 7 is a side elevation of the container sleeve, the lower half being shown in section to show the means provided to support the bearing sleeves, also showing the position of a pocket that carries an elliptical shaped transverse-cut-worm-gear. Fig. 8 is a side elevation, partly in section, of the complete outer casing which is shown partly in elevation, the same having the major part broken away in order to show in section parts of the container sleeve and bearing sleeves, also the internal drive gear. Fig. 9 is a broken portion of certain portions shown in Fig. 8, showing the details of the oil gland closure and other details, the same being in end elevation. Fig. 10 is an enlarged detail view showing certain parts appearing in the left end of Fig. 2. Fig. 11 is a plan view of a portion of the ring locking device. Fig. 12 is an enlarged plan and a projected end elevation of one of the ovoid or double-cone worm gears alone. Fig. 13 is an enlarged detail showing a portion of the bearing sleeve and cage arm, taken as looking at the reduced end. Fig. 14 is an enlarged detail portion of the parts shown in Fig. 13, showing these parts in side elevation, a portion of the side arm being removed to more clearly show the series of angle perforations which are disposed in the bearing lining. Fig. 15 is a side elevation of the complete bearing as it would appear assembled in connection with a shaft. Fig. 16 is a plan view of a broken portion of the bearing sleeve, showing same on a greatly enlarged scale, in order to make clear the angular weakening slots. Fig. 17 is an end elevation of the bearing assembled. And Fig. 18 is a detail section, as taken on the line E—F of Fig. 16.

Similar indices denote like parts throughout the several views, the arrows on certain parts indicate the relative direction of rotation of such parts.

The bearing herein described is carried by a suitable base 1.

The bearing proper comprises an outer, relatively stationary casing, which may be of any approved form, which should be formed in two parts indicated by 2 and 2'.

The case I prefer shall be universally adjustable in the base 1 in any well known manner.

The inner diameter of the casing is provided with parallel walls, and there is located near its extreme ends shallow concentric grooves 3 in which is located a ring 22, as in Fig. 2. Also intermediate its ends is formed the recessed diametrical grooves 4 in which are located the flanges 9, and intermediate said grooves 4 a gear portion 5 is formed, which will be hereinafter mentioned.

Within the said casing is mounted a revoluble container sleeve, preferably formed in two parts, 6 and 6', and the two parts are secured together by the screws 34 and 35. Intermediate the ends of said container sleeve is formed the diametral flange 9 which slidably fits into the said companion grooves 4 within the casing. The inner wall portions of said container sleeve are reversely tapered, as indicated at 10 in Fig. 7, the same converge toward the center, and intermediate the ends of the container sleeve are provided threaded portions 36, which will be mentioned hereinafter.

Adjacent the longitudinal parting of said sleeve there are provided concentrically located pockets 11 in which are mounted suitable double-cut worm-gears 12 in such manner as to freely turn within the sleeve. Said worms are provided with threads 12' that engage with the internal left-hand gear teeth 5. Mounted on the said worm pockets are taper screws 13, which secure the gears 12 in alinement and in revolving position. Secured around the shaft 14, and located between the worms 12, is a right-hand spiral gear 15, which is secured to the shaft 14 by the screw 15', and it is in meshing gear with the worm teeth 12' to impart motion to the latter.

It is now evident that as the shaft 14 is turned, in the direction indicated by the arrows, Figs. 1 and 2, that a transverse rotary movement will be imparted to the worms 12, and then by reason of their left-hand gear connection with the gear 5 carried by the casing, that a greatly reduced but continuous roller motion will be imparted to the bearing mechanism which immediately surround the shaft 14, and this roller motion will be in the same direction as that of the shaft 14.

As is well known in practice there is a line of super-pressure and wear exerted by the power driven shaft upon the bearing, which when the bearing is stationary soon distorts the inner periphery of the bearing and permits the shaft to get out of alinement, thereby greatly hastening the dissolution of bearing. Now by mechanically shifting or causing the bearing proper to creep from under the line of pressure, as in this invention, it is evident that all of the surface of the bearing will be brought into service progres-

sively, thereby causing the bearing to wear, if at all, absolutely true, thereby greatly protracting the life of the bearing and preserving the alinement of the shaft. To further preserve the bearing proper it is caused to pass through a head of oil in each revolution, as indicated in Fig. 2.

The bearing proper, above referred to, comprises the bearing sleeves 16, which are carried with their cages 17, which in turn are carried within the tapered walls of the container sleeve 6, all substantially as shown. The construction and operation of the bearing sleeves and the cages, above mentioned, have been shown and described in Letters Patent No. 1,260,635, issued to me March 26, 1918, and therefore it will not be necessary to repeat the same in detail in this instance, as in this instance I use practically the same bearing sleeves and cage mechanism, however the same is much reduced in relative length, and the same is duplicated, also longitudinal separation of the bearing sleeve is provided in this instance, which is merely for the purpose of making it more easily assembled. I have also shown, in this instance, the bearing sleeve 16 as perforated at its reduced parts 16' by forming a series of angle slots 18 therein, as in Fig. 3, hereinafter referred to.

The bars or arms 17' of the bearing cage are formed in a manner to precisely fit into the reductions formed in the bearing sleeve as shown, for the purpose of controlling the rotatable longitudinal and contractive movements of the bearing sleeves. Said bars are also formed integral with their annular flange portion 20, the latter being formed in such manner as to normally close the ends of the bearing casing, and the inner portion of the same is reduced, as shown at 20', to slidably fit into the casing ends and to register within the ends of the container sleeve 6, as shown in Fig. 10.

Formed centrally within the said reduced flange portion of the cage are annular slots 21 in which are carried annular split ring portions 22, and formed centrally within the flat end portions of the rings are the taper holes 23. Located within the portions of the said cage flanges, and directly adjacent the end portions of said rings are positioned a plurality of taper screw-pins 24, the office of which will be hereinafter referred to.

Annular, interiorly threaded, recesses 25 are also formed in the cage flange 20, adjacent to the shaft openings, in which are thread engaged oil ring glands 26, and in conjunction with the same are provided fiber packing rings 27, the same having angular surfaces corresponding to the inner contour of the glands 26, thus providing positive adjusting end-closures around the shaft openings. There is also provided the locking pins 28, alternating with the taper pins 130

24, and they are formed of sufficient length to extend into adjacent holes 29 which are provided in the ends of the container sleeve 2 to provide means for locking the bearing 5 sleeves and the container sleeve together as a unit when they are under duty.

It is now evident that the several members which rotate continuously around the shaft 14 may be placed in or removed from 10 position within the casing by simply removing the upper member, 2', of the casing, or by assembling or removing them from the ends of the casing, as will be found most convenient.

15 It is now evident that the container sleeve 6-6' is complete as a single unit, while the bearing sleeves and the adjoining parts are in duplicate and interchangeable, and they may be entered into the extreme end of the 20 container sleeve, engaging their companion threads therein, after which they are turned inward sufficiently to register with the pin-holes 29 where the sleeves are locked together as shown. The bearing cages are 25 also longitudinally separable at their flanged portions that they may be free to be removed vertically from their alining positions with the sleeves.

The adjoining portions of the split rings 30 22 are positioned within their companion grooves 3 and 21 and they may be expanded by the adjusting screws 24, thus fixing the longitudinal position of the bearing cages.

It should be understood that having reduced 35 the great cause of inefficiency in parallel bearings to a minimum, by the simple mechanism herein described of rotative reinforcement and compensation, there will in practice remain a small but evenly worn and 40 absolutely true clearance after a time, between the shaft and the bearing sleeves, the adjustment and compensation of which is provided as follows: The bearing sleeves are formed sufficiently larger in diameter than 45 the shaft carried thereby. Therefore by withdrawing the lock-pins 28 from their normal positions, and applying a suitable spanner wrench to engage in the holes 32, which are formed in the cage flanges, it is 50 evident that the excess clearance between the shaft and the bearing sleeves may be reduced, by means of a forward turn of the cage members, or increased by a reverse turn of the same to facilitate the thickness 55 of the oil-film as required, this by reason of the above mentioned taper wall and the right hand thread engaging contact that act in relation to the taper walls in a manner to contact or expand radially the bearing 60 sleeve elements. The inclosed oil chamber, or pockets 31, are in fact the entire space within the bearing not occupied by the bearing elements.

The bearing sleeve interiors are formed as 65 plain surfaces in place of the usual inner

grooving of the same which latter ruptures and destroys the film of oil, while the omission thereof tends to prolong the life of the bearing, in this connection slots 18 are so arranged as to reduce the spanner wrench 70 pressure required to compress the sleeve, that is causing the sleeve to be somewhat resilient, and also pocketing up the oil, in a manner, and permitting the same to filter evenly by gravity, to the point of least resistance.

A series of channels 33 are provided adjacent, and connecting the groups of angle-slots 18, conveying the oil thereto, also extending in parallel therewith, but spaced 75 outside and beyond the contour of the inner surface of the bearing sleeves.

This bearing may, with suitable pipe connection, be filled with oil under pressure if desired, but in the present instance a partially filled chamber without pressure is provided, as this will answer in most instances.

80 Numeral 38 indicates the small openings that perforate the sleeve linings, and they extend radially inward from the bottom portions of the slots 18, as shown in Fig. 16. Numeral 37, Fig. 18, designates the angle wall partitions disposed between the several angle-slots 18, allowing the sleeves to more 85 readily compress or expand. Numeral 39 indicates the shallow inner-angle grooves that complete the U-shaped passages through the lining. Numeral 16² denotes diametrical reduced portions of the parts 16.

90 The above described invention is the climax of a series of inventions in parallel bearings, the former inventions which have previously developed into patents pertained mainly to maintaining the center of axis of the power driven journal, and to so arrange 100 and proportion the lines of the several metals used in bearings in a manner such as to eliminate excessive initial cost to construct bearings, the coefficient of shrinkage and its kindred troubles, providing compensation 105 for wear.

I desire that it be understood that various changes may be made in the several details of construction, and in the arrangement of the several parts, without departing from 110 the spirit of my invention and without sacrificing any of the advantages thereof.

Having now fully shown and described 115 my invention, what I claim and desire to secure by Letters Patent of the United States, is—

1. A journal bearing comprising in combination with a rotatable shaft, an outer non-rotatable casing surrounding the shaft but spaced therefrom, an inner sleeve fitting 120 around the shaft, and means for automatically and positively revolving said sleeve at a speed less than that of the speed of the shaft.

2. A journal bearing comprising, in com- 125

bination with a rotatable shaft, an outer non-rotatable casing surrounding the shaft but spaced therefrom, inner sleeves fitting around the shaft, a container sleeve rotatably mounted in the casing and adapted to carry the inner sleeves therewith, and means for automatically and positively revolving the container sleeve at a speed less than that of the shaft.

10 3. A journal bearing comprising, in combination with a rotatable shaft, an outer relatively stationary casing surrounding the shaft and spaced therefrom, an inner sleeve construction fitting around said shaft, means 15 for adjusting the fitting of said sleeve construction with relation to the shaft, a containing sleeve slidably connecting the inner sleeve and the casing, means operated automatically by the shaft for rotating the sleeves within the casing positively but at a speed less than that of the speed of the shaft.

4. A justifying bearing comprising, in combination with a rotatable shaft, an outer 25 relatively stationary casing surrounding the shaft, a plurality of inner sleeves fitting around the shaft, means for adjusting said sleeves with relation to the shaft, an outer sleeve surrounding the inner sleeves, means 30 for rotatably connecting the outer sleeve with the inner sleeve, means for closing the apertures in the casing around said shaft, and means for causing all of said sleeves to be rotated positively with the shaft but at a reduced speed with relation thereto.

5. A rotative bearing comprising, in combination with a rotatable shaft, an outer relatively stationary casing surrounding the shaft, inner bearing sleeves fitting on the 40 shaft and adapted to rotate independently thereof, an outer sleeve connected with the inner sleeves, worm gears carried by the outer sleeve, an internal gear formed in the casing and meshing with said worm gears, a 45 spiral gear carried by the shaft and meshing with said worm gears whereby the said sleeves will be automatically revolved around inside the casing in the same direction as the shaft but at a less speed than that of the 50 shaft.

6. A compensating bearing comprising in combination with a rotatable shaft to be supported, an outer relatively stationary casing formed in two parts surrounding the 55 shaft, inner bearing sleeves fitting around the shaft, means for adjusting said sleeves upon the shaft, an outer sleeve connected rotatably with the inner sleeves, a fixed gear rigidly secured to and projecting from 60 around the shaft, worm gears carried revolvably by the outer sleeve and meshing with said fixed gear, and an internal gear formed on the inner face of said casing and meshing with said worm gears whereby the 65 rotation of the shaft at a relatively high speed

will automatically and positively rotate the inner sleeves and the outer sleeve at a comparatively low rate of speed, and means for closing the interior of the bearing whereby a body of oil may be retained therein, all 70 substantially as shown and described.

7. A wear-alining bearing comprising in combination with a rotatable shaft, an outer stationary casing surrounding the shaft, a plurality of longitudinally separable sleeves 75 having their inner reduced end portions spaced apart and slidably engaging an outer reversed cone sleeve, a plurality of longitudinally separable cage devices carried within the said outer sleeve and disposed in the 80 space not occupied by the bearing sleeves, they being the means to control the adjustment of the inner sleeves, closures disposed at the extreme ends of the cages and comprising an annular threaded recess within 85 the cage portion, an angular packing ring having an inclosing angular companion gland engaging with said annular threaded recess of the cage portion, and means automatically operated by the said shaft to continuously roll the bearing mechanism at a 90 greatly reduced speed within the casing, substantially as set forth.

8. An automatic wear-alining bearing comprising in combination with a rotatable 95 shaft, an outer comparatively stationary casing surrounding the shaft, inner bearing sleeves fitting around the shaft, said sleeves having a series of longitudinally spaced tie portions formed on their inner lining parts 100 and adapted to bridge the several sections of the sleeve into a unit, a container sleeve disposed around the bearing sleeve, a plurality of cage-members disposed within the container sleeve and located reversely thereto, 105 means for absolutely closing the ends of the cages around the shaft, means for maintaining the exact longitudinal alinement of the case members with relation to the outer casing and comprising a separable flat ring-like portion carried slidably within and between adjacent grooves provided in both the cage and the casing, screw-cone pins carried by the cage portion and engaging like formed holes provided in the separable margins of the ring to expand the same, and means to automatically revolve the entire inner mechanism of the bearing at a speed less than the speed of the shaft that it supports. 110

9. In combination with a journal bearing 115 or the like, a speed reducing mechanism comprising an internal gear carried by a casing, a fixed worm-gear mounted on a shaft which projects through said casing, a container sleeve revolvably positioned in said casing and spaced from said shaft, spaced-apart supporting sleeve mechanisms fitting around said shaft and revolvably attached within said container, a pair of oppositely positioned transverse cut worm gears revolu- 120

125 130

bly attached to the container sleeve in a manner such as to mesh with said worm gears and also in transverse mesh with the internal gear thereby causing the bearing to roll in the same direction as the shaft but at a greatly reduced rate of speed with relation thereto, all substantially as set forth.

In testimony whereof I have hereunto subscribed my name to this specification in the presence of two subscribing witnesses.
